SEWAGE CONTROL SYSTEM

Francis B. Fillo, St. Louis, Mo., assignor to Minneapolis-Honeywell Regulator Company, Minneapolis, Minn., a corporation of Delaware

Application December 3, 1934, Serial No. 755,667

14 Claims. (Cl. 182—26)

This invention relates to a sewage control system and particularly to a means for preventing the backing up of water or of sewage from a main sewer into a feeder sewer.

5 During heavy storms and cloudbursts, backing up of sewage from street sewer mains through back water traps and into the basements of buildings quite frequently occurs despite the use of back water traps in this connection. Safety devices have been improvised in the past in the form of liquid level controls or other devices of this kind using a float, but these have not proved satisfactory because of the heavy foreign matter prevailing in the sewage which interferes with the operation of the floats and renders such devices just as ineffective as the back water traps commonly employed in these sewage systems.

It is, therefore, an object of this invention to 20 provide an efficient safety device or seal to absolutely prevent the backing up of sewage in a sewage system, which safety device or seal is not affected by foreign matter present in the sewage.

25 Another object is to provide an electrically operated safety device or seal responsive to the height of the sewage in the system.

A further object is to provide a valve that is 30 electrically operated according to the height of a liquid in a system.

A still further object is to provide a control system of the type disclosed hereinafter embodying a grid glow tube to control a valve according to changes in a liquid level.

35 Other objects and advantages will become apparent to those skilled in the art by reference to the accompanying specification and single drawing which diagrammatically illustrates the preferred form of my invention.

40 Briefly, the invention contemplates a valve 13 that is opened and closed by an electric motor 22 which is controlled by means of a relay 35. The relay 35 is in turn controlled by a grid glow tube 46 according to whether or not an electrode 45 assembly 61 is contacted by sewage in a sewer pipe 11.

A sewer main or a street sewer is designated at 10 and is adapted to receive a main building sewer 11. Located in the building sewer 11 is a conventional check valve 12 which is intended to prevent backing up of sewage through the building sewer pipe 11. As pointed out above, however, such a check valve may leak, or because of foreign matter in the sewage it may fail to close, 55 allowing sewage to back up through the building

sewer pipe 11. In order to prevent flooding and damage by such backing up of the sewage, a safety device or seal, preferably in the form of a gate valve 13, is installed above or ahead of the check valve 12 in the main building sewer 11. 5 A sewer riser, designated at 14, empties into the building sewer pipe 11, and the building sewer pipe 11 is extended as at 15 to accommodate other sewer risers.

Extending upwardly from the gate valve 13 10 is a valve stem 16 which is raised and lowered by means of a lever 17 through a slidable connection 18, said lever 17 being pivoted midway to a support 19 secured to the valve 13. The lever 17 is oscillated about its pivot to raise and lower 15 the valve stem 16, and consequently to open and close the valve 13, by means of a connecting rod 20 connected at one end to one end of the lever 17 and at the other end to a crank disc 21. An electric motor designated at 22 rotates 20 the crank disc 21 through 180° to open and close the valve 13, such motor being conventional and having the usual limit stops to prevent over-travel of the motor.

Extending into a suitable conduit opening in 25 the motor are conductors 23, 24 and 25. Conductors 24 and 25 are connected to contacts 26 and 27, respectively, which are engaged alternately by a switch arm 28. A conductor 29 connects the switch arm 28 to a line wire 31, and the conductor 23 is connected to another line wire 30, the line wires 30 and 31 conducting A. C. electricity to the system.

When the switch arm 28 engages contact 27, the motor 22 is energized to open the valve 13, 35 as shown in the drawing, and when the switch arm 28 engages the contact 26, the motor is energized to close the valve 13.

The relay 35 has a core 36, a coil 37 enclosing the core 36, and a frame 38 for supporting the 40 coil 37, the frame 38 being grounded as at 39. The core 36 is mechanically connected to the switch arm 28 by means of a connecting rod 40 so that when the coil 37 is energized the core 36 is attracted to the left to move the switch arm 45 45 from contact 26 into engagement with contact 27, and when the coil 37 is deenergized the switch arm 28 is moved from the contact 26 into engagement with the contact 27 by some means, such as a spring (not shown).

41 designates generally a step-up transformer having a primary coil 42 which is connected to the line wires 30 and 31 by means of conductors 43 and 44, respectively, and a secondary coil 45.

A multi-electrode discharge tube is designated 55

generally at 46 and preferably comprises a triple electrode glow tube, often referred to as a grid glow tube, having an anode 47, a cathode 48, and a control electrode 49, sometimes termed a grid.

- 5 5 Grid glow tubes of this type are old in the art, and a specific description of the structure and operation thereof is not considered necessary, it being sufficient to state that as long as the control electrode or grid 49 has a high negative 10 charge, current cannot flow from the anode 47 to the cathode 48, but when the control electrode 49 is grounded to reduce the high negative charge, current is allowed to flow from the anode 47 to the cathode 48.
- 15 15 The cathode 48 is connected to one end of the secondary 45 of the transformer 41 by means of conductors 50 and 51. The anode 47 is connected to one end of the coil 37 of the relay 35 by means of the conductors 52 and 53, and the other end 20 of the coil 37 is connected to the other end of the secondary 45 of the transformer 41 by means of conductors 54 and 55. Located between the conductors 52 and 55 in a manner to partially 25 shunt the coil 37 of the relay 35 is a condenser 56, the purpose of which will be pointed out more specifically hereafter.

The control electrode or grid 49 of the grid glow tube 46 is connected by means of a conductor 58 to a contact 62 of the electrode assembly 61 which is located in the top of the building sewer pipe 11 between the street sewer 10 and the check valve 12 and insulated therefrom by means of an insulator 63. Because of the insulator 63, a high negative charge is maintained 30 on the grid 49, but due to the fact that the insulator 63 is not a perfect insulator, the high negative charge might drain off from the grid 49 because of leakage through the insulator 63 between the contact 62 and the pipe 11, which pipe 35 is effectively grounded. In order to compensate for this slight amount of leakage, an impedance preferably in the form of a variable condenser 60 is interposed between the cathode 48 and the grid 49 by means of a conductor 59, whereby the 40 high negative charge may be maintained on the grid or control electrode 49.

The operating circuit for the relay 35 which operates the switch 28 is completed from the secondary 45 of the transformer 41 through conductor 55, conductor 54, coil 37 of relay 35, conductor 53, conductor 52, anode 47, the gap between anode 47 and cathode 48, cathode 48, conductor 50, and conductor 51 back to the secondary 45 of the transformer 41. As long as the control 50 electrode 49 is insulated so that a high negative charge is maintained on the control electrode 49, no current can flow from the anode 47 to the cathode 48, and the above circuit is therefore 55 open, and the invention is shown in such position in the drawing. If the contact 62 is grounded as by sewage backing up and engaging it, the high negative charge is drawn off from the control electrode 49, the tube 46 breaks down and glows, and current is allowed to flow from anode 60 65 47 to cathode 48 thereby closing the above circuit to energize the relay 35.

It will be noted at this point that the anode 47, the coil 37 of the relay 35, and the lower end of the secondary 45 of the transformer 41 are 70 maintained at substantially ground potential because of the capacity effect between coil 37 and frame 38 and the connection of the frame 38 of the relay 35 to the ground as at 39, and that a high potential with respect to ground is maintained in the upper portion of the secondary 45 75

of the transformer 41 and the cathode 48 because of the existing potential in coil 45 and because of the effective ground at the lower end of coil 45. Also, a high potential with respect to ground is maintained on the grid 49 which results in a negative charge on the grid 49 during the operating half of the cycle because of the relatively low impedance of the condenser 60 and the relatively high impedance of the insulator 63 of the sewer electrode 61.

Assuming that the parts are in the positions shown in the drawing, the valve 13 is open, and sewage is flowing from the building through the building sewer pipe 11 past the check valve 12 and emptying into the main sewer 10, and the 15 valve is maintained in the open position because sewage is not contacting the contact 62 of the electrode 61 in the pipe 11. Should the sewage in the main sewer 10 back up and reach a level so as to engage contact 62 of the electrode 61, the high negative charge is drained off from the control electrode 49 which allows current to flow from the anode 47 to the cathode 48 to energize the coil 37 of the relay 35 to move the switch 28 from contact 27 into engagement with the contact 26 to energize the motor 22 and to close the valve 13 by means of the linkage interposed between the motor 22 and the valve 13. With the valve 13 closed under such circumstances if there should be any leakage through the check 30 valve 12 either because of poor seating or because of foreign matter in the sewage preventing the check valve 12 from closing, or for any other reasons, sewage is prevented from backing 35 up through the building sewer pipe 11 into the building.

The variable impedance 60 interposed between the cathode 48 of the control electrode 49 serves to desensitize the glow tube 46 in the manner pointed out above so that current may flow from the cathode 48 to the anode 47 to open the valve 13 only when sewage engages the contact 62 of the electrode 61.

Due to the fact that current used for the power 45 means is alternating current and that the glow tube 46 passes current in only one direction therethrough, the coil 37 of the core 35 would ordinarily be subjected to an extremely irregular 50 pulsating direct current. In order to smooth out the pulsations of this pulsating direct current on the relay 35, the condenser 56 is interposed between the conductors 52 and 55 across the coil 37 which acts in the nature of a capacity to lower the high points of the pulsations and to raise 55 the low points whereby a fairly even pull on the core 36 of the relay 35 is maintained.

From the above, it is seen that I have invented an efficient safety device or seal which absolutely prevents the backing up of sewage in a 60 sewage system, which safety device or seal is not affected in any manner whatsoever by foreign matter present in the sewage.

Various modifications may be made in the system embodying my invention without departing 65 from the spirit and scope thereof, and I desire, therefore, that only such limitations shall be placed thereon as are imposed by the prior art or are set forth in the appended claims.

I claim as my invention:

- 70 1. In a sewage system of the class described, a main sewer, a feeder sewer emptying therein, an electrically operated valve in said feeder sewer, an electrode in one of said sewers below said valve, and means connected to said electrode for 75

controlling said valve whereby said valve is closed when sewage contacts said electrode.

2. In a sewage system of the class described, a main sewer, a feeder sewer emptying therein, an electrically operated valve in said feeder sewer, an electrode in one of said sewers below said valve, and means connected to said electrode including a relay for controlling said valve whereby said valve is closed when sewage contacts said electrode.

3. In a sewage system of the class described, a main sewer, a feeder sewer emptying therein, an electrically operated valve in said feeder sewer, an electrode in one of said sewers below said valve, and means for controlling said valve including a multi-electrode discharge tube having its control electrode connected to said sewer electrode whereby said valve is closed when sewage contacts said sewer electrode.

4. In a sewage system of the class described, a main sewer, a feeder sewer emptying therein, an electrically operated valve in said feeder sewer, an electrode in one of said sewers below said valve, and means for controlling said valve including a triple electrode glow tube having its control electrode connected to said sewer electrode, and an impedance electrically connected to two of the electrodes of the glow tube for desensitizing said glow tube whereby said valve is closed only when the sewage contacts said sewer electrode.

5. In a sewage system of the class described, a main sewer, a feeder sewer emptying therein, a valve movable to open and closed positions and located in said feeder sewer, an electric motor for opening and closing said valve, an electrode in one of said sewers below said valve, and means connected to said electrode for energizing said motor whereby said valve is closed when sewage contacts said electrode.

6. In a sewage system of the class described, a main sewer, a feeder sewer emptying therein, a valve movable to open and closed positions and located in said feeder sewer, an electric motor for opening and closing said valve, a switch for controlling the operation of said motor, an electrode in one of said sewers below said valve, and means connected to said electrode for operating said switch whereby said valve is closed when sewage contacts said electrode.

7. In a sewage system of the class described, a main sewer, a feeder sewer emptying therein, a valve movable to open and closed positions and located in said feeder sewer, an electric motor for opening and closing said valve, a switch for controlling the operation of said motor, an electrode in one of said sewers below said valve, and means for operating said switch including a multi-electrode discharge tube having its control electrode connected to said sewer electrode whereby said valve is closed when sewage contacts said sewer electrode.

8. In a sewage system of the class described, a main sewer, a feeder sewer emptying therein, a valve movable to open and closed positions and located in said feeder sewer, an electric motor

for opening and closing said valve, a switch for controlling the operation of said motor, an electrode in one of said sewers below said valve, and means for operating said switch including a triple electrode glow tube having its control electrode connected to said sewer electrode, and an impedance electrically connected to two of the electrodes of the glow tube for desensitizing said glow tube whereby said valve is closed only when the sewage contacts said sewer electrode.

9. In a sewage system of the class described, a main sewer, a feeder sewer emptying therein, a valve movable to open and closed positions and located in said feeder sewer, a check valve in said feeder sewer between said valve and said main sewer, and means associated with said feeder sewer between said check valve and said main sewer for opening and closing said first valve.

10. In a sewage system of the class described, a main sewer, a feeder sewer emptying therein, a valve movable to open and closed positions and located in said feeder sewer, a check valve in said feeder sewer between said valve and said main sewer, and means associated with said feeder sewer between said check valve and said main sewer for opening and closing said first valve according to the height of sewage below said check valve.

11. In a sewage system having a main sewer and a feeder sewer, an electrically operated valve in said feeder sewer and movable to open and closed positions, a check valve in said feeder sewer between said electrically operated valve and said main sewer, and means including an electrode associated with said feeder sewer between said check valve and said main sewer to close said electrically operated valve when sewage contacts said electrode.

12. In a system of the class described, a liquid containing means, a pipe emptying therein, an electrically operated valve in said pipe, an electrode in said liquid containing means, and means for controlling said valve including a multi-electrode discharge tube having its control electrode connected to said electrode in said liquid containing means whereby said valve is closed when liquid contacts said electrode in said liquid containing means.

13. In a system of the class described, a liquid containing means, an electrically operated valve controlling the supply of liquid into said containing means, an electrode in said containing means to be engaged by the liquid therein, and means associated with said electrode and said electrically operated valve to close said valve when the liquid engages said electrode.

14. In a system of the class described, a liquid containing means, an electrically operated valve controlling the supply of liquid into said containing means, an electrode in said containing means to be engaged by the liquid therein, and electrical relay means associated with said electrode and said electrically operated valve to close said valve when the liquid engages said electrode.

FRANCIS B. FILLO.
